Primary Examiner—Robert M. Spear*Attorney, Agent, or Firm*—Connolly Bove Lodge & Hutz LLP**[57]****CLAIM**

The ornamental design for a pattern for absorbent sheet material, as shown and described.

DESCRIPTION

The sole FIGURE is a plan view of the pattern for absorbent sheet material showing my new design.

The broken line boundary of the claimed design indicates that the design has indeterminate length and width and defines a portion of the absorbent sheet material to which the pattern is applied, it being understood that the pattern repeats uniformly throughout the design.
